UNITED STATES PATENT OFFICE

148,809

DESIGN FOR A DEVICE FOR RELEASING SNAGGED FISHING LURES OR BAITS

Eugene F. McDonald, Jr., Chicago, Ill.

Application March 4, 1946, Serial No. 127,104

Term of patent 14 years

(Cl. D31—4)

To all whom it may concern:

Be it known that I, Eugene F. McDonald, Jr., a citizen of the United States, residing at Chicago, in the county of Cook and State of Illinois, have invented a new, original, and ornamental Design for a Device for Releasing Snagged Fishing Lures or Baits, of which the following is a specification, reference being had to the accompanying drawings, forming a part thereof.

Figure 1 is a front elevational view of a device for releasing snagged fishing lures or baits, showing my new design;

Figure 2 is a side elevational view of the same; and

Figure 3 is a top plan view thereof.

I claim:
The ornamental design for a device for releasing snagged fishing lures or baits, as shown.
EUGENE F. McDONALD, JR.
